UNITED STATES PATENT OFFICE.

ASBURY O. LEONARD, OF DETROIT, MICHIGAN.

EAR-DRUM.

No 824,998.

Specification of Letters Patent.

Patented July 3, 1906.

Application filed April 8, 1905. Serial No. 254,450.

To all whom it may concern:

Be it known that I, ASBURY O. LEONARD, a citizen of the United States of America, and a resident of Detroit, in the county of Wayne 5 and State of Michigan, have invented certain new and useful Improvements in Ear-Drums, of which the following is a specification.

This invention relates to improvements in artificial ear-drums; and the object thereof is 10 to provide a device of its class which will be highly sensitive to sound and constructed so as to adjust itself to fit the auditory canal without exerting serious pressure on the walls thereof.

15 The above object is accomplished by the construction illustrated in the accompanying drawings, in which—

Figure 1 is a perspective view of the device. Fig. 2 is a longitudinal central section, 20 and Fig. 3 is an end view.

25 Referring now to the numerals of reference marked upon the drawings, 1 is a sensitive membrane, which is substantially flat and thin and completely covers the end of the cell 2, forming the end thereof.

30 3 is a cylindrical supporting member composed of the same material as the membrane and cell and is made integral therewith. The inner end of the supporting member is contracted, as is also the adjacent end of the cell 2, and an aperture 4 leads from within the supporting member into the cell. A longitudinal depression 5 is made in the side of the supporting member, by means of which the 35 walls of the supporting member may be constricted, as indicated by dotted outline in Fig. 3 of the drawings.

40 The material of which this invention is constructed is preferably of soft rubber or any other adaptable material suited for the purpose.

45 In using this invention the device is inserted into the auditory canal of the ear with the cell 2 extending innermost, so that the membrane 1 will range in proximity to the tympanic membrane of the ear, and it will appear that because of the form of the supporting member and its contact with the 50 walls of the auditory canal the device will thereby be held in its position within the ear. If the material forming the supporting member should become expanded because of the warmth due to its contact with the wall of the auditory canal or if the size of the auditory canal to which the device is applied is

slightly smaller in its diameter than the diameter of the supporting member in its normal state, the supporting member will adjust itself within the canal because of the depression 5, in which event the depressed portion 60 increases in extent and permits the constriction of the supporting member, so that its circumference in the first instance is not increased so as to exert pressure upon the walls of the canal, and that in the latter instance 65 the circumference of the supporting member will be decreased so as to accommodate itself to its place.

70 By this construction the tendency of the drum to adhere to the adjacent walls of the canal, and thereby cause soreness, is materially decreased, and its removal from its place in the ear is accomplished with ease by grasping the outer end of the supporting member with tweezers or any other suitable 75 instrument.

Having described my invention, what I claim as new, and desire to secure by Letters Patent, is—

1. In an artificial ear-drum, a cell; a thin 80 flat membrane forming the end of the cell; and a cylindrical supporting member having a longitudinal depression, and being connected with the cell, the walls of the supporting member and cell being contracted at their intersections to form a reduced opening leading from the cell into the supporting member. 85

2. In an artificial ear-drum, a cylindrical supporting member having in relation with 90 one of its ends a sensitive membrane; and a longitudinal depression in the side of said supporting member which extends throughout the length thereof.

3. In an artificial ear-drum, a sound-cell, 95 one end of which is closed by a thin flat membrane which forms a part thereof; and a supporting member in connection with the cell, the walls of the cell and supporting member being contracted at their intersection to form 100 a reduced opening which affords communication therethrough from the sound-cell into the supporting member.

In testimony whereof I affix my signature in presence of two witnesses.

ASBURY O. LEONARD.
